UNITED STATES PATENT OFFICE

HARVEY CLARENCE MITTENDORF, OF EAST ORANGE, NEW JERSEY, ASSIGNOR TO INTERNATIONAL COMBUSTION ENGINEERING CORPORATION, OF NEW YORK, N. Y., A CORPORATION OF DELAWARE

BIN INDICATOR

Application filed September 10, 1928. Serial No. 304,848.

This invention relates to bin indicators and is particularly useful in connection with containers used for the storage of pulverized fuel which has been prepared for burning in suspension and like materials.

Application of George P. Jackson, Serial Number 291,124 filed July 7th, 1928, and assigned to the same assignee as is the present application illustrates one type of bin indicator of this kind and shows a fluid pressure motor for operation thereof.

It is the primary object of my invention to provide novel operating means for indicators of this type.

15 A further object lies in the provision of novel means for effecting an up and down or reciprocating movement of parts of the device when used in connection with a motor which revolves in one direction.

20 Another object is the provision of novel operating means to permit unlimited movement of certain parts of the indicating device in one direction and to provide limited movement thereof in the reverse direction.

25 These, together with such other objects as may hereinafter appear or are incident to my invention I obtain by means of a construction which I have illustrated in preferred form in the accompanying drawings, wherein

30 Fig. 1 is an elevation of a number of bins showing the indicating and operating mechanism in elevation.

Fig. 2 is a side elevation of the operating mechanism.

35 Fig. 3 is a plan view of the operating mechanism shown in Fig. 2.

Fig. 4 is a sectional elevation taken on the line 4—4 of Fig. 2 looking in the direction of the arrows; and

40 Fig. 5 is a wiring diagram of an indicator.

Referring now to Fig. 1 it will be seen that the four coal bins 7, 7^a, 7^b and 7^c are supplied with coal by means of feed line 30 which has branches 21 leading to the different bins.

45 These branches are controlled by valves 22 which in one position allow the coal to flow on through to the next section of the feed line and in another position divert the flow of coal from the feed line to the particular branch 50 which the valve controls.

In each bin there is a cone 9 which is properly counterweighted by means of counterweight 23 so that it will be sustained by the coal when lowered thereonto. The position of the cone 9 in the bin is indicated on proportional scale 24 by means of a weighted pointer 25 which moves in the slotted tube 26. The counterweight also moves up and down in a tube 27 which is provided with springs 28 at the upper and lower end to soften the impact of the counterweight 23. The connection of the cone, counterweight and pointer will be explained in detail hereinafter.

Considering only the parts above described and disregarding for the moment the effect of the operating motor and mechanism, it should be noted that with the bin full of coal and the cone resting on the surface thereof as the coal is used the cone will drop, following and resting on the receding surface of the coal in the bin. Indication of the position of the cone and thus of the amount of coal in the bin will be given on the scale by the pointer 25 which is properly connected with the cone 9.

However if fresh coal is now fed to the bin at the top the cone will become buried therein for it does not "float" and it is necessary therefore to raise the cone until it emerges from the fresh coal in which it had been buried and then allow it to drop until it comes into contact with the surface of the fresh coal in order to get a true indication of the amount of coal in the bin. Where coal is being fed and used more or less continuously it can be seen that it becomes necessary to raise and lower the cone continuously in order to obtain accurate indication. This is what may be termed a continuous and automatic sounding or a "hunting" movement of the cone and in order to secure such movement I have provided the novel operating mechanism illustrated in detail in Figs. 2, 3 and 4.

The operating mechanism, indicated as a whole by the reference letter A, is mounted on the top of each of the bins upon the frame 10. The small electric motor 11 which runs continuously in one direction is connected by means of a silent chain 12 to a well known form of worm gear reduction unit 13 which

has a shaft 16 driven at reduced speed projecting at each end from the casing of the unit. Slack in the silent chain 12 is taken up by means of the adjustable chain tightener 14 which is secured to the frame 10^a.

The shaft 16 of the reduction unit 13 carries on one end the arm 15 which is fixed to and rotates with the shaft. The arm 15 carries an idling pulley 17 which rotates with the 10 arm and also turns on its own axis. A stationary arm 29 is also secured to the frame 10 and projects outwardly to one side thereof, the end of the arm which is away from the frame 10 carrying idling pulley 20 which lies in substantially the same plane as the idling pulley 17. The line 18 which is connected to the upper part of the cone 9 runs up through an opening in the top of the bin, over the pulleys 20 and 17 and is connected 20 to the drum 19 about which it winds.

This drum 19 is keyed to shaft 31 which is carried in bearings on the two upright standards 32 and 33 which are in turn mounted on the frame 10. The shaft 31 at one end 25 is surrounded by the fixed hollow threaded member 35 and the drum 19 carries a threaded unit at its center which screws onto the fixed member 35. Turning of the drum 19 will therefore cause it to screw onto or off 30 the member 35 and this will impart a movement along the shaft which will allow the line 18 to wind evenly and lie flat on the drum 19.

The drum 19 has a reduced portion 19^a to 35 which the line 34 is connected and about which it winds. The line 34 is connected to the counterweight 23 and runs over idle pulley 36 carried on standard 37 which is secured to the edge of the bin.

The drum 19 also has a still smaller reduced portion 19^b to which is connected the 40 line 38 and about which it winds. The line 38 is connected to the weighted pointer 25 and runs over idling pulley 39 which is carried by the standard 37.

The shaft 31 also carries a ratchet wheel 40 which is fixed to the shaft 31. The dog 41 which cooperates with this ratchet wheel 40 is carried by arm 42 which in turn is 45 mounted on a shaft 43 which is carried by a projection 44 on the standard 33. When the dog 41 engages the teeth of the ratchet wheel it prevents the wheel from turning and thus locks the shaft 31 and the drums 19, 19^a and 50 19^b in position. When the dog disengages the ratchet wheel the shaft and drums are 55 free to revolve.

Operation of the dog is controlled by cam 45 which is fixed to the end of shaft 16 of 60 the gear reduction unit 13. This cam operates a weighted lever 46 which is connected to the arm 42 which carries the dog. In the position shown in Fig. 2 the shaft 31 and drums are locked in position by the dog. In 65 Movement of the cam 45 in a counterclock-

wise direction will lift the lever 46 which will cause the dog to swing to the left and disengage the ratchet wheel thus releasing the shaft and drum and leaving them free to revolve.

The adjustable weight 47 is carried by the lever 46 to insure contact of the lever with the cam in all positions.

It will be observed that drum 19 is held in position during one half of a revolution of 75 shaft 16 and cam 45 and that the drum 19 is free to revolve during the other half of the revolution of shaft 16 and arm 15. In other words the drum is unlocked on downward movement of the arm 15 and is locked 80 in position on upward movement of the arm by virtue of the cam, lever and locking dog arrangement.

It will be observed that the part of the drum 19 about which the line 18 winds is 85 larger than the part 19^b about which the line 34, to the counterweight, winds. This gives a certain amount of leverage to the cone 9 which on this account does not have to be any heavier than the counterweight in 90 order to overbalance it. Considering this leverage, the relative weight of the cone and counterweight should be such that the drum 19 will revolve in one direction, (when unlocked) under influence of the weight of the 95 cone, when it is not in contact with the coal in the bin and will revolve in the other direction under influence of the weight of the counterweight when the cone is resting in the surface of the coal in the bin. This means 100 that the drum will revolve under influence of the weight of the counterweight to take up any slack in line 18 which is connected to the cone. However when the line 18 becomes taut the weight of the cone will then prevent 105 further movement.

If desired the drums 19 and 19^a may be of the same size and in such case a proper readjustment of the relative weight of cone and counterweight should be made. I have 110 made drum 19^a smaller than drum 19 in order to provide a shorter range of travel for the counterweight and thus reduce the length of the counterweight tube.

In considering the above the influence of 115 the weighted pointer 25 has been disregarded. This will have a slight effect however and as shown in the drawings its influence is added to that of the cone 9. This should be properly compensated for in the counterweight 23.

The operation is as follows:

With motor 11 running the shaft 16 of the gear reduction unit will revolve at a moderate speed and the arm 15 carrying pulley 17 125 will rotate with it. The cam 45 will also turn with the shaft 16.

If the bin is now empty and the cone 9 at the top, with the parts in the position shown in Fig. 2 the drum 19 is locked and 130

the cone will therefore be suspended in the bin for the line 18 cannot unwind from drum 19. With a little further movement of shaft 16 however the projecting portion of the cam 45 will engage and lift lever 46 unlocking the shaft 31 and permitting drum 17 to turn. The cone 9 will now drop to the lower part of the bin running out the line 18 or drum 19, for it more than balances the counter-weight 23 as above pointed out. The counter-weight will be drawn to the top of its range and the weighted pointer will drop to the lower part of the scale to indicate that the bin is empty.

15 Further movement of arm 15 in a counter-clockwise direction will further lower the cone 9 for this movement will allow the line 18 to extend in a straight line from pulley 20 to drum 19 when the pulley 17 reaches the 20 lowest position in its orbit. In this position the pulley 17 is tangent a line drawn between the surface of drum 19 and pulley 20.

After pulley 17 has reached its lowest position it begins to rise, the drum 19 is locked 25 in position and pulley 17 engages and deflects or arches the line 18 by lifting it, thus pulling the cone 9 up until the pulley 17 reaches the top of its orbit (the position shown in Fig. 2) after which the drum 19 is released and if 30 no coal has been admitted to the bin in the meantime the same cycle of operation is repeated, i.e. the cone will be alternately raised and lowered a distance equal to the length of line required to run straight between pulley 35 20 and drum 19 and that required to run from pulley 20 over pulley 17 at the top of its orbit and then to drum 19.

Suppose now that coal is admitted to the bin. When the cone is now lowered it will 40 drop only until it rests on the surface of the coal or it may not drop at all if it has become completely buried in the coal. This will cause slack in the line 18 which will be taken up by turning of the drum 19 under influence of the weight of the counterweight 23 as above pointed out. One or two turns of line 18 may thus be laid on drum 19 which will then be locked in position with this line laid on it when the pulley 17 then engages 45 and arches the line 18, the cone although it will be lifted just the same amount as before, will reach a higher position in the bin for it was in a higher position (on the surface of the newly admitted coal) when the arching 50 was begun. In this way the cone will follow the coal right up to the top of the bin when it is being filled.

If at any time more coal should be used 60 than is put in, the cone will drop to the surface thereof as soon as drum 19 is released.

It will thus be seen that whatever happens to the level of the coal in the bin the cone 9 will always "hunt" the surface thereof and indication thereof will be given on the proportional scale by the weighted pointer 25.

Remote indication of the position of the cone may be obtained by use of a voltmeter 51 (see Fig. 5) which is connected to potentiometer type rheostat 50 which in turn is operated by shaft 31. Rheostat 52 is used to 75 reduce the line voltage so as to give full scale voltmeter deflection with a voltmeter of smaller range than the potential across the line.

What I claim is:—

1. A bin indicator comprising in combination a revoluble drum having a line connected thereto from which a cone is suspended, said cone being adapted to rest on the surface of the material in the bin, another line connected to said drum from which a counterweight is suspended, the relative effect of the cone and counterweight being such that the drum will revolve under influence of the weight of the cone when the cone is free and will revolve under influence of the weight of the counterweight when there is slack in the line to the cone, means for locking and unlocking said drum, means for arching the cone line to move the cone when the drum is locked and an indicator associated with a moving part.

2. A bin indicator comprising in combination a revoluble drum having a line connected thereto from which a cone is suspended, said cone being adapted to rest on the surface of the material in the bin, the said drum revolving in one direction under influence of the weight of the cone when the cone is free, means to revolve said drum in the opposite direction to take up slack in the said line, means for locking and unlocking the drum, means for arching said line to move the cone when the drum is locked and an indicator associated with a moving part.

3. A bin indicator comprising in combination a cone adapted to rest on the surface of the material in the bin, a line from which said cone is suspended movable means to which said line is connected, means for arching said line intermediate said movable means and said cone to move the cone, means for locking said movable means while the line is being arched and an indicator associated with a moving part.

4. A bin indicator comprising in combination a cone adapted to rest on the surface of the material in the bin, a line from which said cone is suspended, movable means to which said line is connected, means for arching said line intermediate said movable means and said cone to move the cone, means for locking said movable means while the line is being arched, means for releasing said line after it has been arched and means for taking up slack in said line while it is released and an indicator associated with a moving part.

5. A bin indicator comprising in combination a cone adapted to rest on the surface of the material in the bin, a line from which said

cone is suspended, a revolute drum to which said line is connected, means for arching said line intermediate the drum and the cone to move the cone, means for locking said drum while the line is being arched and an indicator associated with a moving part.

6. A bin indicator comprising in combination a cone adapted to rest on the surface of the material in the bin, a line from which said cone is suspended, a revolute drum to which said line is connected, means for arching said line intermediate the drum and the cone, means for locking said drum while the line is being arched, means for turning said drum to take up slack in the line and an indicator associated with a moving part.

7. A bin indicator comprising in combination a cone adapted to rest on the surface of the material in the bin, a line from which said cone is suspended, a revolute drum to which said line is connected, means for arching said line intermediate the drum and the cone, means for locking said drum while the line is being arched, means for turning said drum to take up slack in the line comprising a counterweight having a line wound about said drum and an indicator associated with a moving part.

8. A bin indicator comprising in combination a cone adapted to rest on the surface of the material in the bin, a line from which said cone is suspended, a revolute drum to which said line is connected, means for arching said line intermediate the drum and the cone comprising a rotating arm so located as to engage said line during a part of its rotation, means for locking said drum while the line is being arched and an indicator associated with a moving part.

40 9. A bin indicator comprising in combination a cone adapted to rest on the surface of the material in the bin, a line from which said cone is suspended, means for holding one end of said line, means for arching said line intermediate the point at which it is held and said cone, said means comprising a rotating arm so located as to engage said line during a part of its rotation, means for releasing said line after it has been arched and an indicator associated with a moving part.

10. The combination with a bin indicator having a cone which is raised and dropped to hunt the surface of the material in the bin of means for actuating the cone comprising a line secured thereto, a rotating arm adapted to engage said line, means for holding said line when in engagement with the arm and means for releasing said line.

11. A bin indicator comprising in combination a cone adapted to rest on the surface of the material in the bin, a line connected to said cone, a revolute drum to which said line is connected, means for arching said line intermediate the drum and the cone, a motor for actuating said arching means, means for

locking and releasing said drum also actuated by said motor and an indicator associated with a moving part.

12. A bin indicator comprising in combination a cone adapted to rest on the surface of the material in the bin, a line connected to said cone, a revolute drum to which said line is connected, means for arching said line intermediate the drum and the cone comprising a rotating arm so located as to engage said line during its rotation, means for actuating said drum, means for locking the drum while the line is being arched said locking means also being actuated by said actuating means and an indicator associated with a moving part.

13. A bin indicator comprising in combination a cone adapted to rest on the surface of the material in the bin, a line from which said cone is suspended, means for holding one end of said line, means for arching said line intermediate the point at which it is held and said cone, means for actuating said arching means, said actuating means also operating the holding means to hold said line while it is being arched and an indicator associated with a moving part.

14. A bin indicator comprising in combination a cone adapted to rest on the surface of the material in the bin, a line connected to said cone, a revolute drum to which said line is also connected means for arching said line intermediate the drum and the cone comprising a revolute arm mounted on a shaft actuated by a motor, a cone also mounted on said shaft, a lever actuated by said cam, a dog operated by said lever, a ratchet on said drum, said dog being adapted to engage said ratchet to lock the drum and an indicator associated with a moving part.

15. A bin indicator comprising in combination a cone adapted to rest on the surface of the material in the bin, a line connected to said cone, a revolute drum to which said line is also connected means for arching said line intermediate the drum and the cone comprising a revolute arm mounted on a shaft actuated by a motor, a cam also mounted on said shaft, means operated by said cam to lock and unlock the drum and an indicator associated with a moving part.

16. A bin indicator comprising in combination a cone adapted to rest on the surface of the material in the bin, a line connected to said cone, a revolute drum to which said line is also connected, means for arching said line intermediate the drum and the cone comprising a revolute arm mounted on a shaft associated with a motor, a cam also mounted on said shaft, locking means operated by said cam for locking the drum when the line is being arched and an indicator associated with a moving part.

17. A bin indicator comprising in combination a cone adapted to rest on the surface

of the material in the bin, a line connected to said cone, a revolute drum to which said line is also connected, means for arching said line intermediate the drum and the cone comprising a revolute arm mounted on a shaft associated by a motor, a cam also mounted on said shaft, locking means operated by said cam for locking the drum when the line is being arched, means for turning said drum when unlocked to take up slack in the line and an indicator associated with a moving part.

18. The combination with a bin indicator having a cone which is raised and dropped to hunt the surface of the material in the bin, of a line connected to said cone and to a revolute drum, means for locking said drum, means for arching the line when the drum is locked and means for turning said drum when it is unlocked to take up slack in the line.

19. The combination with a bin indicator having a cone which is raised and dropped to hunt the surface of the material in the bin, of a line connected to said cone and to a revolute drum, the weight of the cone being sufficient to revolve said drum in one direction when the line is wound about it, means for locking said drum, means for arching the line when the drum is locked and a counterweight having a line connected to and wound about said drum, the weight of the counterweight being sufficient to turn the drum in the other direction when the weight of the cone is not acting to turn it.

20. The combination with a bin indicator having a cone and means associated therewith whereby the cone is raised and dropped to hunt the surface of the material in the bin, of a line connected to said cone and to a revolute drum, the weight of the cone being sufficient to revolve said drum in one direction when the line is wound about it, and a counterweight having a line connected to and wound about said drum, the weight of the counterweight being sufficient to turn the drum in the other direction when the weight of the cone is not acting on it.

21. The combination with a bin indicator having a cone which is raised and dropped to hunt the surface of the material in the bin of a line connected to said cone and to a revolute drum, the weight of the cone being sufficient to revolve said drum in one direction when the line is wound about it, means for locking and unlocking said drum, means for arching the line when the drum is locked and means for turning said drum in the other direction when the drum is unlocked and when the weight of the cone is not acting to turn it.

22. The combination with a bin indicator having a cone which is raised and dropped to hunt the surface of the material in the bin of a line connected to said cone and to a rev-

olute drum, the weight of the cone being sufficient to revolve said drum in one direction when the line is wound about it, means for locking and unlocking said drum, means for arching the line when the drum is locked, and means tending to turn said drum in the opposite direction when the drum is unlocked and when the weight of the cone is not acting to turn it.

In testimony whereof I have hereunto signed my name.

HARVEY CLARENCE MITTENDORF.
